UNITED STATES PATENT OFFICE.

JOHN T. ROBINSON, OF PHILADELPHIA, PENNSYLVANIA.

IRONING-BOARD.

1,279,914.

Specification of Letters Patent. Patented Sept. 24, 1918.

Application filed March 23, 1918. Serial No. 224,249.

To all whom it may concern:

Be it known that I, JOHN T. ROBINSON, a citizen of the United States, residing at Philadelphia, in the county of Philadelphia 5 and State of Pennsylvania, have invented a new and useful Ironing-Board, of which the following is a specification.

This invention relates to ironing boards, one of its objects being to provide a device 10 of this character which can be folded into a compact body when not in use and which can be readily set up for use.

A further object is to provide an ironing board including a supporting frame to 15 which the board proper is hingedly connected, there being means adjustably connected to the frame for supporting hanging fabrics out of contact with the floor.

With the foregoing and other objects in 20 view which will appear as the description proceeds, the invention consists of certain novel details of construction and combinations of parts which will be hereinafter more fully described and pointed out in the 25 claims, it being understood that various changes may be made in the construction and arrangement of the parts without departing from the spirit or sacrificing any of the advantages of the invention as set forth 30 in the appended claims.

In the accompanying drawings the preferred form of the invention has been shown.

In said drawings—

Figure 1 is a side elevation of the device 35 set up for use.

Fig. 2 is a plan view thereof.

Fig. 3 is an end elevation.

Fig. 4 is a section on line 4—4, Fig. 2.

Referring to the figures by characters of 40 reference, 1 designates an open frame to the ends of which are hingedly connected supports 2 foldable inwardly under the frame when the structure is collapsed. Any suitable means may be provided for holding the 45 supports against folding. For example, and as shown in Figs. 1 and 3 staples 3 or the like can be provided on the outer faces of the supports and on the ends of the frame 1 to receive holding strips 4 insertable longitudinally and which fit snugly.

The ironing board *per se* has been shown at 5 and is hingedly connected to one end of the frame 1, as shown at 6, this board being provided with the usual fabric covering 55 7 and normally resting flat upon the frame 1. The free end of the board is ex-

tended between the upper ends of the strips 4 at one end of the structure so as to be held thereby against lateral shifting upon the frame 1.

Hangers 8 depend from the sides of the frame 1 at the ends thereof and have hooks 9 at their lower ends. In these hooks are removably mounted rods 10 to which are secured the ends of a fabric sheet 11. The 60 fabric sheet is adapted to be wound or rolled upon one of the rods and said rod is provided with a crank 12 whereby it can be rolled readily. A staple 13 extends from the said rod and by shifting the rod longitudinally the staple can be brought to a position from which it will move into engagement with the adjacent hook 9 when the fabric sheet begins to unwind. The sheet 11 thus can be held slack to any desired extent and will constitute an efficient means for holding fabrics off of the floor while they are being ironed. By rotating crank 12 in one direction the staple or loop 65 on its rod 10 will move off of the hook 9 70 engaged thereby and by then shifting said rod longitudinally the rod can be rotated to wind up or pay out the fabric sheet, as desired.

What is claimed is:—

1. The combination with an open frame, and an ironing board movably connected to one end of the frame and adapted to rest flat upon said frame, of supports movably connected to the ends of the frame, fastening strips detachably connected to and extending above the frame and supports for holding the supports against movement relative to the frame, the free end portion of the ironing board being fitted between and held against lateral displacement by the upper ends of the fastening strips at one end.

2. The combination with an open frame, and an ironing board movably connected to one end of the frame, of foldable supports connected to the ends of the frame, hooked hangers depending from the frame, rods detachably seated in the hooks of the hangers, a sheet connected to the rods and extending 95 under the frame and board, means for rotating one of the rods to roll the sheet on or unroll it from said rod, and means upon said rod for engaging the hook of one of its hangers to hold the rod against rotation 100 to unwind the sheet.

3. The combination with an open frame,

and an ironing board movably connected to one end of the frame, of foldable supports connected to the ends of the frame, hooked hangers depending from the frame, rods 5 revoluble in the hangers, a sheet connected at its ends to the rods, a loop outstanding from one of the rods, and means for rotating said rod to wind or unwind the sheet, said rod being shiftable longitudinally to 10 bring the loop into position to move into

engagement with the adjacent hook when the sheet begins to unwind, thereby to hold the rod against rotation.

In testimony that I claim the foregoing as my own, I have hereto affixed my signature in the presence of two witnesses.

JOHN T. ROBINSON.
